FIG. 3.

FIG. 4.

FIG. 5.

FIG. 6.

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

CONCAVING HEELS.

Application filed May 10, 1927. Serial No. 190,335.

My invention relates to a heel concaving machine adapted to impart a tapering concavity to the top of the heel.

It is my object to provide a safe and accurate tapering heel concaving mechanism adapted to impart with great accuracy the exact taper desired to the concavity of a heel used in such shoes known as arch preserver shoes. These heels it is my object to mount in a moving heel clamp of such predetermined form that by reason of its cooperation with the guides in my machine the exact concavity and taper will be imparted to each heel of a given lot so that accurate fit will be insured between the heel and the rest of the arch preserver shoe, while at the same time securing great rapidity of production with the minimum of skill necessary on the part of the operator and with the maximum safety for the operator.

It is my further object to provide a machine which is universal with respect to different sizes of heels. It is an additional object to provide a machine that requires the minimum of judgment on the part of the operator and will only necessitate two simple movements on the part of the operator so that unskilled labor can be largely utilized and the factor of skill and judgment substantially eliminated, thereby economizing on labor costs and making it possible to produce heels in large quantities, of great accuracy, with workmen or workwomen of substantially no experience.

Referring to the drawings,

Fig. 1 is a top plan view of the machine with the heel about to be concaved;

Fig. 2 is a top plan view of a portion of the machine showing the heel holder in its second position;

Fig. 3 is a section on the line 3-3 of Fig. 1;

Fig. 4 is a large top plan view of the heel holder;

Fig. 5 is a section on the line 5-5 of Fig. 4;

Fig. 6 is a section on the line 6-6 of Fig. 5.

Referring to the drawings in detail, 1 designates the legs supporting the frame 2. This frame carries a series of journal brackets 3 in which is journaled the cutter shaft 4. The cutter shaft carries the cutter 5 on the end thereof which cutter is provided with the usual teeth 6. The cutter shaft is

driven by the belt 7 from the pulley 8 mounted on the armature shaft 9 of the motor 10. This cutter is adapted to project through a slot 11 in a pivoted cutter table 12 pivoted at 13 between the set screws 15 carried in the bracket 16 on the table 12. This table 12 has mounted thereon a pair of spaced guides 14 held in position by the clamping screws 17 mounted on bolts in the slots 18 of the pivoted table 12. The table itself is adjusted in position by the set screw 19.

Between these guides 14 and guided thereby is the heel clamp and holder which consists of a pair of clamping arms 20 pivoted at 21. The arms are actuated through a handle 22 mounted adjacent their pivot. The arms are connected together by an adjusting clamping plate 23 which is pivoted at 24 on one arm and extends over the other arm where a slot in the plate designated 25 is engaged by a set screw 26 and a wing nut 27 carried by the clamping arm which is overlapped by the plate 23. Each of these arms are cut away as at 28 to permit the cutter to pass up through between the arms to engage with the heel 29. This heel is positioned by T shaped stops designated 30 which engage the forward edge of the heel and the sides thereof. The inner ends of the T shaped stops, as at 31, extend beyond the arms 20 but above the level of the table 12 so that the cutter can rotate beneath said extensions 31 without coming in contact with them. It is apparent that the heel holder is so arranged as to position the heel and hold it in position to be concaved while at the same time the holder is adjustable to varying sizes and types of heels.

These arms 20 have their upper faces inclined so that the heel is held at an incline 95 with the result that the concavity 32 on the top of the heel will have its bottom 33 tapered, the bottom being of greater depth at the front of the heel than at the rear thereof. The arms of the holder are provided 100 with two guiding surfaces, a relatively long surface 35 and a relatively short surface 34 at an angle to one another. In addition to this a stop 36 is provided for limiting the movement, away from the operator, of the 105 holder. This stop is adjustable.

Operation.

The operator takes the heel and places it upside down in the heel holder and clamp 110

so that what is normally the top of the heel now is placed in the bottom position because the heel is inverted. The forward edge of the heel is placed against the T shaped overhanging portions 31 while the sides of the heel are engaged by the sides 30 of the positioning stops on the arms 20. The wing nut 27 is clamped to hold the heel in position which is now suspended over the opening 28 in the heel holder. The heel holder is then moved so that its side 34 is against one guide 14 and its longer opposite side 35 is against the other guide. The operator grasps the handle 22 and pushes the holder slowly forward over the cutter so that the material is cut away from the cutter with the desired concavity and taper. The holder is then withdrawn and its position is altered in that the side 35 of the holder which formerly engaged the guide 13 is moved away from that guide so that only its side 34 engages with the guide. Accordingly the other guide is now engaged by the side 35 and is disengaged from the side 34 of that arm of the holder. This spaces the heel at a different angle to the cutter and it is again moved with the holder into cutting position for the completion of the concavity and the taper.

30 By these two simple operations of pushing the heel forward and back again and the simple clamping of the heel in the holder, I am enabled to provide a mechanism that will give a perfect concavity and taper of predetermined size to the heels without the exercise of any particular ingenuity, experience or skill on the part of the operator. If the operator is supplied with a group of heels of different kinds, with the proper holder or the proper taper, and with the guides adjusted by a foreman, the ordinary workman or workwoman can perform this delicate operation with substantially no experience, skill or instruction, and with the utmost safety as the operator has no occasion for coming in engagement with the cutter or going near the cutter. The movement of the holder is limited by the adjustable stop 36.

50 It will be understood that I desire to comprehend within my invention such modifications as may be necessary to adapt it to varying conditions and uses.

Having thus fully described my invention, what I claim as new and desire to secure by Letters Patent, is:

1. In a heel concaving machine, a supporting platform, a cutter rotating therethrough, a guide, a heel holder having a tapering surface adapted to be moved over the cutter, and clamping members arranged to hold the heel in position to be operated on by the cutter when the holder and heel are moved over the cutter.

60 2. In a heel concaving machine, a support-

ing platform, a cutter rotating therethrough, a guide, a heel holder adapted to be moved over the cutter, said holder having a tapered surface being adapted to hold the heel at a position inclined to the surface of the supporting platform, and guiding surfaces on the sides of the holder.

70 3. In a heel concaving machine, a cutter, a table mounted over said cutter through which the cutter is adapted to project, guides mounted on said table, a heel holder having guide engaging edges adapted to carry a heel over the cutter.

75 4. In a heel concaving machine, a cutter, a table mounted over said cutter through which the cutter is adapted to project, guides mounted on said table, a heel holder having a tapered surface and having guide engaging edges adapted to carry a heel over the cutter, said heel holder having edges on either side angularly disposed to one another so that the holder may be moved along the guide in an angular position.

80 5. In a heel concaving machine, a table, a cutter adapted to project through said table, spaced guides, a heel holder having a tapered surface and clamping members so arranged to hold the heel in position to be operated by the cutter when the holder and heel are moved over the cutter and guiding surfaces on the sides of the holder for engaging with the guides.

85 6. In a heel concaving machine, a table, a cutter adapted to project through said table, spaced guides, a heel holder having a tapered surface and clamping members so arranged to hold the heel in position to be operated by the cutter when the holder and heel are moved over the cutter and guiding surfaces on the sides of the holder for engaging with the guides, said guiding surfaces being angularly disposed with respect to one another.

90 7. In a heel concaving machine, a table, a cutter adapted to project through said table, spaced guides, a heel holder having a tapered surface and clamping members so arranged to hold the heel in position to be operated by the cutter when the holder and heel are moved over the cutter and guiding surfaces on the sides of the holder for engaging with the guides, said guiding surfaces being angularly disposed with respect to one another, one portion of the surface being relatively long and the other relatively short so that the holder will engage the guide on one side on its long surface and the guide on the other side on the short surface.

105 8. In an article of manufacture for use as a heel holder consisting of a pair of pivoted clamping arms, clamping shoulders thereon, said arms being cut away adjacent said shoulders to support a heel over the cut away portion and means to adjustably clamp a heel between said arms and shoulders

whereby a cutter may operate on the heel through the cut away portion in the arms, spaced guides and guiding surfaces on the sides of the heel holder for engaging with the guides.

9. In an article of manufacture for use as a heel holder consisting of a pair of pivoted clamping arms, clamping shoulders thereon, said arms being cut away adjacent 10 said shoulders to support a heel over the cut away portion and means to adjustably clamp a heel between said arms and shoulders whereby a cutter may operate on the heel through the cut away portion in the 15 arms, the surface of said arms tapering so as to hold the heel at an inclined position with respect to the cutter, spaced guides and guiding surfaces on the sides of the heel holder for engaging with the guides.

20 10. A new article of manufacture for use as a heel holder in a concaving machine consisting of the combination of a pair of arms pivoted to one another, a handle, angular clamping shoulders on each arm adjacent 25 cut away portions in the arms, means to adjustably clamp said arms with respect to one another and overhanging projecting shoulders from the ends of the arms to limit the forward movement of the heel but so ar- 30 ranged as to permit a cutter to pass beneath said overhanging projections so that the cutter can project through the cut away portions of the arms to concave the heel, spaced guides and guiding surfaces on the 35 sides of the heel holder for engaging with the guides.

11. A new article of manufacture for use as a heel holder in a concaving machine con-

sisting of the combination of a pair of arms pivoted to one another, a handle, angular 40 clamping shoulders on each arm adjacent cut away portions in the arms, means to adjustably clamp said arms with respect to one another and overhanging projecting 45 shoulders from the ends of the arms to limit the forward movement of the heel but so arranged as to permit a cutter to pass beneath said overhanging projections so that the cutter can project through the cut away 50 portions of the arms to concave the heel, 55 said arms tapering from one end to the other in order to present the heel to the cutter in an inclined position, spaced guides and guiding surfaces on the sides of the heel holder for engaging with the guides.

12. In a heel concaving machine, a cutter, an adjustable platform through which the cutter projects, guides, a tapering heel holder adapted to clamp a heel therebetween and means to limit the movement of the 60 holder mounted on the table, spaced guides and guiding surfaces on the sides of the heel holder for engaging with the guides.

13. In a heel concaving machine, a cutter, a holder for the heel adapted to hold it in 65 inclined position, means to support the holder with respect to the cutter in a horizontal plane, means to guide laterally the holder and the heel, said cutter being ar- 70 ranged to rotate transversely of the direction of movement of the heel which is being presented to the cutter, spaced guides and guiding surfaces on the sides of the heel holder for engaging with the guides.

In testimony whereof, I affix my signature.
GEORGE CLAUSING.
